UNITED STATES PATENT OFFICE.

WILLIAM J. JEFFERY, OF CHICAGO, ILLINOIS, ASSIGNOR OF ONE-HALF HIS
RIGHT TO LEROY B. FIRMAN, OF SAME PLACE.

IMPROVEMENT IN FOUNTAIN-LAMPS.

Specification forming part of Letters Patent No. 151,133, dated May 19, 1874; application filed
February 16, 1874.

To all whom it may concern:

Be it known that I, WILLIAM J. JEFFERY, of Chicago, in the county of Cook and State of Illinois, have invented certain Improvements in Fountain-Lamps, of which the following is a specification:

This invention relates to that class of illuminating apparatus in which the lamp or system of lamps is connected, by a pipe or pipes, to a reservoir containing the oil or other liquid combustible to supply the several burners placed below said reservoir.

In the present invention each burner is made so that it regulates itself, and allows the oil to flow in only so fast as it is consumed. To accomplish this I employ for the lamp a jacket connected to the supply-pipe, into which the oil may flow through an ingress-aperture in the bottom, and rise to fill it. Within this jacket is placed the oil-pot for containing the supply for the flame. The bottom of this vessel is fitted with a projecting pin of a conical or needle shape, adjusted so that when the fluid in the jacket rises far enough to overflow into the oil-pot, and causes it to fill and sink, the pin will enter the ingress-aperture and close it, shutting off the supply of oil, and preventing the lamp from overflowing. When the wick has drawn out the oil from the oil-pot, the oil in jacket, being higher than in the oil-pot, causes it to float, and, in rising, lifts the pin, admitting another supply of oil in the jacket, which, overflowing in the pot, causes it to sink and shut off the supply, as before, until the oil is again withdrawn from the oil-pot.

Having thus set forth the principle of my self-regulating device, I will proceed to describe it more particularly.

In the accompanying drawing, which forms a part of this specification, Figure 1 represents a central vertical section of the lamp. Fig. 2 is a transverse horizontal section of the same. Fig. 3 is a diagram illustrating the operation of the reservoir. Fig. 4 is a small-scale section of the lamp-pot and jacket, and Fig. 5 is an enlarged section of the needle-valve.

In the several figures the same letters denote the same parts.

In said drawing, A represents the exterior oil-containing jacket, connected at the bottom

to the supply-pipe B, which communicates with the reservoir C, which may be placed at the top of the house, or in any elevated position, so that a sufficient head is given to supply all of the burners. This jacket A is fitted at top with a suitable cover, a, to which is screwed or otherwise secured the wick-tube and other necessary parts of the burner D. E is the oil-pot contained within the jacket A, and fitted at the bottom with the concave plug or pin e, which sets down into the ingress-aperture f in the base of the jacket, and when the oil-pot is down as far as it will go the point of this pin completely fills said aperture and prevents the oil from entering the jacket. The oil-pot is pierced near the top with several holes, g, through which the oil in the jacket, when it rises to their level, will flow into the oil-pot. G is a perforated or wire-gauze guard surrounding the wick-tube and attached thereto, serving as a guard to prevent the wick from coming in contact with the sides of the oil-pot, while it does not prevent the free advent of the oil to said wick. It also serves as a flame-proof safety contrivance. The aperture f, from the jacket A to the tube B, is made very small at the bottom, so that it may be filled completely by the point of the plug e, which presents so small a surface to the oil in the tube B that the pressure of said oil upward is incapable of raising the weight of the oil-pot.

The operation is as follows: The oil-pot is raised first by the hand until the jacket is filled by the oil overflowing through the holes g. The flow is then shut off by the oil-pot descending by its own weight, closing the aperture f with the pin e. Now, when the lamp is lighted the wick draws its supply of oil from the oil-pot, which, presently becoming partially empty, floats upward in the oil within the jacket, and, withdrawing the pin e, opens the ingress-aperture to admit more oil within the jacket, which, overflowing into the oil-pot, causes it to sink when full, and thus shut off the supply. This regulation is automatic and constant, and enables me to place the burner at any distance from and below the oil-reservoir C, because the head of oil, acting merely upon the end of the pin e, is unable to overcome the weight of the oil-pot, and thus the

supply to the wick is always kept up without danger of the lamp overflowing at whatever level it may be, provided only that it be kept at a level lower than the fountain-head—the reservoir C.

In Fig. 3 of the drawing this is illustrated by placing several lamps, connected with a single reservoir, at different levels.

To prevent the small aperture of ingress from becoming closed up by particles of foreign matter in the oil, or from becoming gummed up with the oil itself, I apply to the pipe B, below the aperture in each jacket, a bit of wire-gauze netting, *i*, of a very fine mesh, which strains the oil and purifies it before it reaches said aperture.

Having thus fully described the construction and operation of my invention, what I

claim as new, and desire to secure by Letters Patent, is—

1. The combination of the oil-containing jacket A with the oil-pot E and ingress-valve governed by the rising and sinking of said oil-pot, substantially as specified.

2. The combination of the reservoir C, tube B, jacket A, oil-pot E, and the valve governed by the rise and fall of said oil-pot, substantially as specified.

3. The perforated guard G, surrounding the wick-tube and wick, in combination with the burner D, the floating oil-pot E, and jacket A, substantially as specified.

W. J. JEFFERY.
